Primary Examiner — Jae Liang*Assistant Examiner* — Riya Salil Kamat(74) Attorney, Agent, or Firm — Lisa Foundation Patent Law Clinic; Anthony Bonfiglio(57) CLAIM

The ornamental design for a golf tee tool, as shown and described.

DESCRIPTION

FIG. 1 is a perspective view of a golf tee tool, showing my new design.

FIG. 2 is a back elevation view thereof.

FIG. 3 is a front elevation view thereof.

FIG. 4 is a top view thereof.

FIG. 5 is a bottom view thereof.

FIG. 6 is a right-side elevation view thereof; and,

FIG. 7 is a left-side elevation view thereof.

1 Claim, 4 Drawing Sheets(56)
